UNITED STATES PATENT OFFICE.

IRA H. SPENCER, OF WEST HARTFORD, CONNECTICUT, ASSIGNEE TO THE SPENCER TURBINE CLEANER COMPANY, OF HARTFORD, CONNECTICUT, A CORPORATION OF CONNECTICUT.

CLEANING APPARATUS.

1,072,783.

Specification of Letters Patent.

Patented Sept. 9, 1913.

Application filed November 3, 1908. Serial No. 460,932.

To all whom it may concern:

Be it known that I, IRA H. SPENCER, a citizen of the United States, and a resident of West Hartford, in the county of Hartford and State of Connecticut, have invented 5 a new and Improved Cleaning Apparatus, of which the following is a specification.

My invention relates generally to the class of devices employed for removing dust or 10 like material from various places, and more especially to the class of such devices as employs a current of fluid, the force of which is utilized to displace the dust, and the object of my invention among others is to provide 15 a device of this class in which the dust or other material removed from certain places shall not accumulate in other equally objectionable places; and a further object of the invention is to provide a device having 20 novel features of advantage and utility.

A form of device in the use of which the objects sought may be attained is illustrated in the accompanying drawings, in which—

Figure 1 is a perspective view of an apparatus embodying my invention. Fig. 2 is a view on enlarged scale of a portion of the apparatus shown in Fig. 1, with parts broken away to show construction, the tool being shown removed from its receiver. Fig. 3 is 25 a detail view in cross-section of the brush. Fig. 4 is a detail view showing a modified form of construction.

It has been found desirable to provide in numerous places such means for the removal 30 of dust or similar material as will prevent such matter removed from one place from being deposited in other equally objectionable places, and at the same time it is important that the means for such removal 35 shall be readily at hand, easily manipulated, and that shall not require in its use operations other than those actually required in the manipulation of the device to remove such dust or other matter. Such an apparatus 40 is especially convenient and has manifold advantages in the erasure of chalk or like marks from blackboards or similar places, and while the device is not in any sense limited to use in connection with such 45 devices, I have selected such for the purpose of illustration and description of the invention herein.

In the accompanying drawings the numeral 6 denotes in general an apparatus for 50 causing flow of fluid, in the special class of

devices illustrated and described herein this being an exhauster, or one that creates a flow of fluid as of air through the pipes in a manner to cause a suction at the inlets to the tools. This exhauster may be of any desired 60 form and construction and is suitably connected with a main 7 located and extending to such places as may be required. This exhauster may be suitably located as in the cellar of a building, as a school building, 65 store or the like, and the mains extended throughout the building and having branches 8 leading to such places as may be required for the location of the cleaning tools.

The numeral 10 denotes a portion of a 70 blackboard having a ledge or shelf 11 and underneath this shelf, the latter preferably forming a top therefor, a box or housing 12. The branch 8 extends into this housing in any suitable manner and is connected with a valve casing 13 in which a valve 14 is located and movable to engage a valve seat 15 at the end of the branch 8, the valve thus serving to close the opening from said branch into the valve casing 13. This valve casing has 75 a chamber 16 with an outlet 17. A valve stem 18 supports the valve 14, this stem passing out of the chamber 16 through a suitable device as a stuffing box 19.

A valve lever 20 is pivotally mounted as 80 on a link 21 on the valve casing, and a spring 22 is employed to move the lever to draw the valve 14 away from its seat. A connecting rod 23 pivotally attached to the lever 20 extends to a receiver 24. This receiver, in the form of construction shown, extends through an opening 25 in the shelf or top 11 of the housing 12 and is freely movable in said opening. The connecting rod is secured to the receiver so that the latter in its movement will operate the valve lever 20.

A fluid conductor 26 is connected with the valve casing 13 and a tool 27 is attached to this conductor. This tool may be of any 100 suitable form and construction for the special purpose required of it, in the form of device herein shown this tool being a brush having a rubbing surface common to the kind of brushes employed in the erasure of 105 chalk marks from blackboards.

The conductor 26 is attached preferably to one end of the brush and communicates with a chamber 28 therein, this chamber having an inlet or mouth 29 extending through 110

the erasing surface 30. This erasing surface may be composed of any comparatively soft material, as wool or cotton, common to devices of this class.

5 It will be seen from the illustration, taken in connection with the above description, that when the brush is in place in its receiver, the weight of the brush will cause the receiver to rest in its lowermost position, in 10 which position the valve 14 will be closed so that there will be no current of air through the conductor 26. It will be understood that the exhauster 6 is in continual operation.

15 When it is desired to erase marks from the blackboard, or to remove dust from any place, as from the shelves or counters of a store, or from articles deposited thereon, the tool, as the eraser 27 is moved from its position in the receiver for the purpose required. The receiver being thus relieved of the weight of the tool, the spring 22 raises the lever 20, thus lifting the valve 14 from its seat and causing a flow of air through 20 the valve chamber toward the exhauster. This causes an inflow through the inlet 29 of the tool or eraser, and as the latter is moved over the surface to erase the chalk marks or to remove dust, all the dust stirred 25 up by the erasing surface 30 is carried in at the inlet. This effectually removes the dirt from the room and prevents its accumulation upon other articles or surfaces. It will be seen from this construction that no act is 30 required on the part of the operative to cause a flow of the air currents, or to start up a device to cause such flow, the simple act of removing the tool from its receiver serving to place the device in operation for the purpose of removing the dust or dirt.

40 The spring 22 is of sufficient strength to open the valve and the weight of the eraser or tool 27 will readily overcome the action of the spring owing to the greater leverage 45 obtained by reason of connecting the receiver 24 to the outer end of the lever 20, and this will be readily accomplished with a brush or tool of normal or convenient weight.

45 The form of device shown in Fig. 4 is in its general operation similar to that of Fig. 2. In Fig. 4, however, a balanced valve is employed. Two valve seats 31 are located in the dividing wall 32 between the inlet chamber 33 and outlet chamber 34 of the 50 valve body 35. The valve stem 36 is connected up in a manner similar to the construction shown in Fig. 2, the parts in fact being the same with the exception that in place of the spring 22 secured to the lever 55 20 between its ends, a spring 37 exerts its force upon the outer or free end of the lever, this spring being simply sufficient to overcome the weight of the receiver 24.

55 It will be noted that the valve is so located that when a tool is not in use there is no

communication between the valve chamber and the branches or mains leading to the exhauster. That is, the valve is so located as to cut off entirely all parts which are liable, by reason of their construction, to 70 leak.

75 While I have shown and described herein the preferred embodiment of my invention, I do not limit myself to the use herein described, or to the construction of the apparatus shown, as these may be departed from to a greater or lesser extent without avoiding the invention.

I claim—

1. A valve to control the flow of a fluid, 80 a flexible tubular conductor for flow of fluid past said valve, a tool connected with said conductor and having an inlet for said fluid, a movably mounted tool receiver arranged to move under the influence of the weight 85 of said tool, and an unbroken connection between said receiver and valve to operate the latter.

2. A valve to control the flow of a fluid, 90 a flexible tubular conductor for flow of fluid past said valve, a tool having an inlet for said fluid and connected with said conductor, a vertically movable receiver for the tool actuated by the weight of the latter, and connections between said receiver and 95 valve to operate the latter.

3. An apparatus for creating a current of fluid, a tool having an opening for the flow of said fluid, a conduit for said fluid between said tool and current creating means 100 and including a flexible conductor, a valve in said conduit between said current creating means and flexible conductor to control the flow of fluid, means to support the tool and that end of the conductor secured 105 thereto when said parts are not in use, and an operative connection between said supporting means and the valve to operate the latter upon the removal of said tool, said connection being arranged to permit lengthwise movement of the flexible conductor within said support in the operation of the tool.

4. An apparatus for creating a current of fluid, a tool having an opening for flow of 115 said fluid, means including a flexible conductor connected to said tool for conducting said flow, a valve to control said flow, said valve being located between the flexible conductor and the current creating means, a 120 housing for said flexible conductor, a tubular receiver movably located in an opening in the wall of the housing, a connection between said receiver and valve to operate the latter, and a tool secured to the flexible conductor and arranged to be held by said receiver.

5. An apparatus for creating flow of a fluid, a tool having an opening for the passage of fluid, a connection between said 130

tool and said current creating means and including a flexible conductor, a valve located to control the flow of fluid through said conductor, a tubular receiver arranged 5 to receive said tool and through which receiver said flexible connection extends and a connection between said receiver and valve to operate the latter.

6. A valve to control the flow of a fluid, 10 a flexible tubular conductor for flow of fluid past said valve, a tool having an inlet for said fluid and connected with said conductor, a movably supported receiver for said tool, and a connection between said receiver

and valve to impart force of movement of 15 the receiver to operate the valve.

7. A valve to control the flow of fluid, a flexible tubular conductor for flow of fluid through said valve, a tool having an opening for the passage of said fluid, a tool receiver connected with said valve and operating to close the valve when the tool is in the receiver, and means for opening said valve. 20

IRA H. SPENCER.
